(57) **CLAIM**

The ornamental design for a confocal microscope having a positionable imaging head for cellular imaging of skin, other living tissue and biological processes, as shown.

DESCRIPTION

FIG. 1 is an elevational perspective view from the right side of a confocal microscope having a positionable imaging head for cellular imaging of skin, other living tissue and biological processes;

FIG. 2 is a top perspective view thereof;

FIG. 3 is a front elevation view thereof;

FIG. 4 is a top view thereof;

FIG. 5 is a right side elevation thereof;

FIG. 6 is a bottom view thereof; and,

FIG. 7 is an enlarged fragmented perspective view of the imaging head portion thereof.
